CLAIM

The ornamental design for a ceiling fan motor housing, as shown and described.

DESCRIPTION

FIG. 1 is a top perspective view of a ceiling fan motor housing showing my new design, shown in the environment of a ceiling fan;

FIG. 2 is a bottom perspective view of the ceiling fan motor housing of FIG. 1, but shown without the ceiling fan environment;

FIG. 3 is a side view thereof;

FIG. 4 is a top view thereof; and,

FIG. 5 is a bottom view thereof.

The broken lines illustrate a ceiling fan, and portions of the ceiling fan motor housing. None of the broken lines form part of the claimed design.
